United States Patent Office

Des. 210,867
Patented Apr. 30, 1968

210,867

BOTTLE

Yuriko Kuroda, Tokyo, Japan, assignor to Kabushiki
Kaisha Kobayashi Kose, Tokyo, Japan

Filed Feb. 16, 1967, Ser. No. 5,839

Claims priority, application Japan Sept. 14, 1966

Term of patent 14 years

(Cl. D9—154)

Fig. 2

Fig. 1

Fig. 3

Fig. 5

Fig. 4

Fig. 6

FIG. 1 is a perspective view of a bottle embodying my new design;

FIG. 2 is an elevational view thereof, the side opposite that shown being the same in appearance; and

FIG. 3 is a top plan view thereof;

FIG. 4 is another perspective view showing a modified form of my new design;

FIG. 5 is an elevational view thereof, the side opposite that shown being the same in appearance; and

FIG. 6 is a top plan view thereof.

I claim:

The ornamental design for a bottle, as shown.
